1

It is a well known fact that the human organism is stimulated by variations which put the accommodation mechanism in function. This also concerns the surrounding air and its temperature. After having stayed some time in a room with even temperature, it is felt as a stimulus to go out into the open air during some minutes for refreshing and breathing the fresh outside air. Aeration by window opening aims at the same end. However, it is often difficult or impossible to realize aeration through window openings, for instance in town due to the dusty outside air or due to the noise in the streets. Furthermore, even where intermittent refreshment in this manner is possible, the window openings allow an excess amount of cooling, so that the whole room becomes cold and uncomfortable, and some time is required to restore the room to the desired normal temperature.

The present invention concerns devices for improvement of heating, ventilating or air-conditioning plants through an intermittent supply of cool air, in localities, where people are working sedentarily during several hours.

The object of the device is to force from time to time cool and refreshing air to the localities, especially in the living and breathing zones without extensive cooling of the whole room. During great periods of the year the air can be taken direct from the outside in the temperate zones of the earth, possibly with cleaning, and is introduced by means of a fan and a duct system into the room to be treated. During hot days and in hot zones on the other hand, it is necessary to cool and also to humidify the air before forcing it into the room. The force periods can be controlled automatically by a time clock, which starts and stops the plant at certain intervals.

The performance of the device is illustrated by the following examples which concern a room heated by radiators, but it can as well be applied to localities heated by hot air or provided with radiant heating and also for such localities that are equipped with complete air conditioning plants.

In the drawings:

Figure 1 is a diagrammatical horizontal view of one embodiment of the invention.

Figure 2 is a diagrammatical horizontal view of another embodiment according to the invention.

Figure 3 is a diagrammatical vertical view of a part of the invention illustrated in Fig. 2.

Figure 1 represents a locality, such as a work room, which is heated by means of eight radiators

1a—1h in the usual manner. Two air ducts 2 and 3 are arranged alongside two outer walls of the locality or in their proximity. The ducts are provided with openings adjacent the zones or stations (work benches, desks, or the like) for directing air toward said stations, which openings, on the drawing are marked by arrows. To the two ducts 2 and 3 are connected fans 4 and 5 with their motors 6 and 7 respectively. The fan motors 6 and 7 are controlled by a time clock 8, which can be set beforehand for convenient periods and intervals. The fans 4 and 5 can be equipped with filters for cleaning the air and with coils for cooling the air during the hot season.

15 Figures 2 and 3 show another embodiment of the invention and represent a locality which is heated by radiators and is ventilated with tempered air by means of an air-conditioning plant. The latter comprises two ducts 9 and 10 for the supply of air to this locality (indicated by arrows). The two ducts are united to a trunk 11 connected to the discharge opening of a fan 12 which is driven by a motor 13. An inlet opening 14 of the fan 12 is connected to a heating coil 15 and a cooling coil 16. The air enters the coils 15 and 16 from a mixing chamber 17, provided with a mixing damper 18 by means of which the air can be taken either from the locality through the opening 19 or from the outside through the opening 20 or is a mixture of air from both in an intermediate position of the damper 18. The temperature of the inlet air is automatically controlled by means of a heating valve 21, a cooling valve 22 and the damper motor 23 which normally are operated by a thermostat 24 which realizes a suitable temperature of the supplied air. The thermostat 24 is doubled by an identical thermostat 25 which is set on a lower temperature. The thermostat 24 can for instance be set on 25° C. and the thermostat 25 on 10° C. By means of a time clock 26 the thermostat 24 is connected normally to govern the control devices 21, 22 and 23 so that when heating is required to maintain the temperature of the supplied air at 25° C. 25 (77° F.), heating valve 21 is opened and cooling valve 22 is closed; and when cooling of the air is required to maintain this temperature, heating valve 21 is closed and cooling valve 22 is opened. At certain times and with certain intervals the thermostat 24 is disconnected by the time clock 26 and replaced by the thermostat 25 for a certain period, whereby the temperature of the inlet air for a short time is put down to 10° C. in the same manner in order to realize the cooling effect described above. In order that this

cooling effect shall be perceptible in the living zone without having to pass through the whole locality and to cool it down, it is suitable to arrange the supply ducts for the air in the way that is illustrated in Figure 3, which represents a vertical section of part of a treated room. The radiator 27 is placed under the window and the working desk 28 is placed in front of it. The air duct 29 has its supply opening 30 directed in such a way that the air jet reaches the person sitting before the desk in the breathing zone. During the time cool air is being introduced into the room, the radiators 27 continue to supply heat to the room at about the normal rate so as to maintain the room at about the normal temperature. As the thermostats 24, 25 are in the air duct rather than in the room, they do not respond to the room temperature, but merely control or regulate the temperature of the air admitted to the room. In fact where the radiators 27 are controlled by a room thermostat, they may even tend to increase the heat input of the room to compensate for the cool air introduced.

The invention is not limited to the examples above, but can be modified without abandoning its principle. Thus the supply of the air can be made directly into the locality without distribution by ducts. An air conditioning unit can be connected to two different systems of ducts, one of which works in the normal way with constant temperature, whereas the other system realizes the intermittent cooling periods having its supplementary cooler which is started and stopped in the same way as described above for Figure 3.

Having now described my invention, what I claim as new, and desire to secure by United States Letters Patent, is:

1. An apparatus for air conditioning a room providing a plurality of stations therein comprising: an air supply means including a duct having a plurality of openings communicating with said stations to provide local temperature effects therein; heating means and cooling means in the air supply means; two thermostatic con-

trol means for the heating and cooling means in the air supply means for maintaining predetermined different temperatures of the air passed through the duct to said openings; a return duct connecting said room with the air supply means; a thermostatically controlled damper controlling admission of return air and fresh air to said supply means; and a time clock for alternately selectively rendering effective said heating and cooling means for intermittently forcing cool air for periods of short duration, and heated air at a normal rate, through said openings to said stations.

2. An apparatus for air conditioning a room providing a plurality of stations therein comprising: an air supply means including a duct having a plurality of openings communicating with said stations to provide local temperature effects therein; heating means and cooling means in the air supply means; two thermostatic control means for the heating and cooling means in the air supply means for maintaining predetermined different temperatures of the air passed through the duct to said openings; and a time clock for alternately selectively rendering effective said heating and cooling means for intermittently forcing cool air for periods of short duration, and heated air at a normal rate, through said openings to said stations.
